TIP-DELIVERING BOWLING BALL

Carmen D. Jones, Arlington, Va.

Application January 27, 1948, Serial No. 4,640

1 Claim. (Cl. 232—1)

1

This invention relates to improvements in bowling balls for duck-pins.

It is customary to give tips to the pin boys in bowling alleys and this is accomplished by rolling or throwing coins down the alleys. Frequently the coins fail to reach their destination and fall flat on the playing surface or roll into the gutters or off the particular alley.

An object of the invention is the provision of a bowling ball having an enlarged pocket therein to receive a container for coins as tips to the pin boys. The outer or exposed end of said container being curved to conform to the spherical surface of the ball, said ball being provided with a distinctive color or indicia for setting it apart from the other balls.

A further object of the invention is the provision of a bowling ball having an enlarged pocket therein to receive a container having an outer closed end flush with the curved surface of the ball so that the ball will roll smoothly along the playing surface of the alley. The inner end of the side walls of the pocket being flared to receive outwardly projecting spring-pressed members on the inner open coin-receiving end of the container for retaining said container in position within the pocket, said ball being so marked that it will be recognized readily as the "tip ball," the container being releasable from the pocket to recover the coins deposited therein.

The invention consists in the novel construction, arrangement and combinations of parts hereinafter more particularly described and claimed.

In the drawings,

Figure 1 is a vertical section taken through the center of a bowling ball disclosing a vertical section of a removable coin container.

Figure 2 is a view in elevation of the container removed from the ball.

Figure 3 is a top plan view of the container illustrated in Figure 2.

Figure 4 is a side view in elevation of an instrument employed for removing the container from the ball.

Figure 5 is a view in elevation of a modified form of the container.

Figure 6 is a vertical section of the modified form of container seated in a pocket in a bowling ball.

Figure 7 is a horizontal section taken along the line 7—7 of Figure 5 of the modified form of the container.

Referring more particularly to Figures 1 to 3, inclusive, 10 designates a bowling ball employed

2

especially for duckpins. Said ball is provided with a radial pocket 11 which is formed by boring a hole therein or the socket may be formed during molding. The balls are made from the same materials as are employed in the manufacture of bowling balls, however, they may be provided with a distinctive color or indicia which may be applied directly to the surface of the ball for ready recognition of the special purpose of the ball.

The side wall of the pocket is preferably cylindrical although it may assume some other geometrical design. The inner end of the pocket is flared as shown at 12 for a purpose which will be described presently.

The bottom 13 of the pocket is flat and disposed at one side of the center of the ball 10. A container 15 is cylindrical in form and has a smaller cross-sectional area than the pocket 11 so that the container may be fitted readily into the pocket. The container is made preferably of spring metal in order that resilient fingers 16 may be formed at the inner end of the container, when the side wall thereof is provided with a plurality of vertical slits 17. The fingers at the upper ends are pressed outwardly as shown at 18 to form an increased diameter at the inner end of the container for frictional engagement of the fingers with the side wall of the pocket to aid in retaining the container in the pocket. The fingers, adjacent the free ends, are bent outwardly to form curved ribs 19 which are adapted to seat circumferentially in the flared portion 12 of the pocket 11 and which cooperate with the frictionally-engaged fingers for maintaining the container in the pocket until released manually.

An integral closure 20 forms the outer end of the container and is provided with a coin slot 21. The outer face of the closure conforms to the spherical surface of the ball so that the ball will roll smoothly over the playing surface of the bowling alley. A spring finger 22 has one end secured at 23 to the inner surface of the cover 20 with the free end disposed across the slot to prevent the loss of coins from the container. A coin may be inserted through the slot and the free end of the finger will be forced away from the slot by the coin which will fall to the bottom of the pocket 11.

An instrument 25, Figure 4, may be employed for removing the container 15 from the pocket 11. The instrument includes a handle 26, a shank 27 and a key 28 adapted to be inserted through the coin slot 21 and turned by the handle for placing the key transversely of the slot. A pull

on the handle will remove the container for the recovery of the coins in the pocket.

Figures 5 to 7, inclusive, illustrate a modified form of the container. A cylindrical container 30 is seated in the pocket 11 in the ball 10 and has an open bottom and a closed top. A closure or cap 31 has an externally-threaded cylindrical flange 32 screwed into the internal threads of the cylinder 30. A knurled portion 33 aids in rotating the closure. The closure has a peripheral shoulder 34 seated on the outer end of the cylinder. A coin slot 21 in the closure is protected against the loss of coins by the spring finger 22 extending across the slot. The outer surface of the cover conforms to the spherical surface of the ball.

The inner end of the container is provided with diametrically-disposed passages 35 to receive spring-pressed fingers 36 projecting into the flared portion 12 of the pocket 11 to retain the container from accidental discharge. A semi-circular flat spring 37 is seated against the inner wall of the container and not only carries the pins or fingers 36 but retains them in the flared portion 12 of the pocket.

The bowlers are provided with a number of the balls equipped with the coin containers. When it is desired to forward a tip to a pin boy, a coin is inserted through the slot 21 past the spring 22 whence it will fall to the bottom of the pocket 11. The ball is then rolled down an alley. The distinguishing marks or color on the ball will be sufficient to attract the attention of the boy who will remove the container by the instrument 25. After the coin has been obtained, the empty container will be reinserted in the pocket and the ball will be returned along the usual runway.

When the container 30 is employed and the pin boy finds that the coin is too large for passing the spring 37, he will unscrew the cover 31.

After the coin has been taken from the container, the cover will be replaced as will the container after which the ball will be returned along the runway to its starting point. The spring-actuated means in the form of the ribs 19 in Figure 2, or the pins 36 in Figure 7, seated in the annular flared portion 12 of the pocket retains the respective containers in the pockets 11.

What is claimed is:

10 The combination with a bowling ball having a cylindrical pocket extending inwardly from a peripheral surface thereof, the bounding ball of said pocket contiguous to its terminating end being flared to provide an annular seat, of a coin delivering container embracingly received and supported within said pocket, said container having an open bottom and a top and being provided with a plurality of longitudinally extending circumferentially spaced slots extending from 20 the open bottom thereof, the portions of said sleeve intermediate said slots being bent outwardly to form a plurality of fingers for frictional engagement with the bounding wall of said pocket, and the free ends of each of said fingers being bent arcuately outwardly to form ribs for frictional engagement within said annular seat.
